UNITED STATES PATENT OFFICE

HENRY L. BOE, OF MINNEAPOLIS, MINNESOTA

GARMENT HANGER

Application filed December 31, 1931. Serial No. 584,051.

This invention relates to garment hangers.

At the present time, dresses and other garments are commonly stored and displayed in department stores by hanging the dresses and other garments on ordinary bow type garment hangers. These ordinary bow type garment hangers serve quite well for the purpose of hanging men's suits, overcoats and the like, but they are not found satisfactory for many types of women's dresses, such as evening gowns, low necked dresses and the like. Evening gowns and low necked dresses readily slip off such ordinary bow type garment hangers, particularly during the constant handling of such articles of clothing by clerks in stores. Such delicate dresses are often soiled and sometimes ruined due to the fact that they slip from such hangers onto the floor. Although various types of garment hangers have been devised, including arms which clamp such dresses and other garments against a bow, most of these arm type hangers have been proved to be unsuccessful for use in department stores, either because the clerks will not take time and pains enough to position the garment correctly on the hangers, or because of the expense of such hangers.

It is the object of this invention, therefore, to provide a novel and improved garment hanger particularly adapted for use in hanging women's evening gowns and low necked dresses, which hanger is cheap and simple in construction and can be operated with a minimum amount of effort on the part of the user of the same to clamp the article of clothing in place and prevent the same from slipping off the hanger.

To this end, generally stated, the invention consists in the novel parts and novel combinations of parts hereinafter defined in the claims and described in the following specification, made in connection with the accompanying drawing, wherein like reference characters refer to the same or similar parts throughout the various views, and in which,

Fig. 1 is a view in side elevation illustrating an embodiment of the present invention, the movable parts being shown in

one position in full lines and in a second position in dotted lines;

Fig. 2 is a section taken on the line 2—2 of Fig. 1 as indicated by the arrows; and

Fig. 3 is a section taken on the line 3—3 of Fig. 1 as indicated by the arrows.

In accordance with the invention, there is provided a bow 4, which is shown in the present embodiment illustrated, as being formed from wood, although if desired this bow may be formed from metal such as wire. Applied to the central portion of the bow 4 and upstanding therefrom, is a hook 5 by means of which the bow may be suspended from a horizontal rod or bar, or the like. A pair of spring arms 6 shown in the present embodiment as being formed from wire, are used in connection with the bow 4. These spring arms 6 have upturned ends 6a sunk within bores in the lower side of the bow 4 in outwardly spaced relation from the center of the bow and the spring arms are further secured to the bow as by means of staples 7 which embrace outwardly extending portions 6b of the arms 6 joining the upturned ends 6a. The staples 7 are driven into the lower surface of the bow 4. The outwardly extending portions 6b of the arms join portions coiled to form coiled springs 6c. The coiled spring portions 6c join lower portions 6d which project normally in substantially horizontal relation below the bow 4. The lower portions 6d extend toward the opposite ends of the bow respectively from the ends adjacent which the coiled spring portions 6c of the arms 6 of which lower portions 6d form a part are disposed and, as viewed in Fig. 1, the two portions 6d cross each other below the central portion of the bow 4. Joining the lower portions 6d are upwardly extending intermediate portions 6e which project upwardly to points above the upper surface of the bow 4. Each intermediate portion 6e is laterally offset in a direction toward the coiled spring portion 6c of the spring arm 6 of which it forms a part, to form a jog or nose 6f. The upper part of the intermediate portion 6e of each arm is turned over the bow 4 and joins an upper

or clamping portion 6g which overlies the bow 4. The clamping portion 6g of each arm 6 projects in a curve toward the opposite end of the bow 4 from the end most closely adjacent which the coiled spring portion 6c of the same arm is disposed and each clamping portion 6g terminates in a loop 6h. Keepers in the form of staples 8 are secured respectively to opposite sides of the bow 4 and the intermediate portions 6e of the arms run through these keepers 8. The spring arms 6 are at all times under spring tension, by reason of the coiled spring portions 6c and also by reason of the lower portions 6d which, in reality, form bar springs, to swing downwardly and retain the clamping portions 6g in clamping relation against the upper surface of the bow 4. The intermediate portions 6e are at all times under spring tension, due to the resiliency of the material forming the arms, to press tightly against the staples or keepers 8 as the spring arms 6 are raised upwardly from their lower position shown in full lines Fig. 1 to their upper position shown in dotted lines Fig. 1. As a result, when the arms 6 are raised upwardly from their lower positions to such a point that the jogs or noses 6f are carried above the keepers 8, the intermediate portions 6e will swing toward the ends of the bow 4 to which the arms, of which the intermediate portions 6e form a part, are attached and the noses 6f will engage with the keepers 8 to prevent the return of the arms 6 to their lower position, as shown in dotted lines Fig. 1.

To place a dress or other article of clothing on the hanger, the operator will grasp the bow 4 about the central portion thereof with the fingers of one hand and will place the thumb of the same hand below the lower portions 6d of the spring arms 6 at the point where these portions cross each other. The thumb will then be raised toward the hook 5 to swing the spring arms 6 upwardly from the full line position shown in Fig. 1 to the dotted line position there shown, or until the noses 6f engage the keepers 8 to hold the clamping portions 6g in spaced relation above the upper surface of the bow 4. It requires but one hand of the operator to thus set the hanger, so that the dress or other garment may be held in the other hand of the operator while the hanger is being set. When the hanger is thus positioned, the dress or other garment may be inserted in place on the bow 4 with the shoulder straps or shoulder portions of the dress or garment depending from the bow. The operator may now press downwardly on the loop portions 6h of the spring arms whereupon the intermediate portions 6e will be swung outwardly toward the respective ends of the bow to cause the release of the noses 6f from the

keepers 8, whereupon the coiled springs 6c and the lower portions 6d, due to their spring tension, will cause the spring arms to swing downwardly to the full line position shown in Fig. 1 thereby causing the clamping portions 6g to clamp against the portions of the garment overlying the upper surface of the bow 4. The garment will then be held so that it will be impossible for the same to slip off the bow 4. When it is desired to remove the garment from the hanger, the spring arms 6 will, of course, be swung upwardly as before described and this movement will set the hanger in position to receive the garment when it is next hung on the hanger.

It will be seen that an extremely simple and efficient hanger is provided. The same movement imparted to the spring arms 6 to release a garment from the hanger, sets the hanger for reception of the garment again and there is thus small likelihood that the garment will be placed on the bow of the hanger without moving the clamping portions 6g to their clamping position. Although it is desirable to form the coiled spring portions 6c in the spring arms, it is not necessary that these portions be provided inasmuch as the natural resiliency of the material forming the spring arms can be relied upon to place the spring arms under the proper tension for the successful operation of the hanger. It is, of course, also possible to vary the configuration of the spring arms considerably to accomplish the desired results. Different types of keepers than the keepers 8 may be used if desired.

It will, of course, be understood that various changes may be made in the form, details, arrangement and proportions of the various parts without departure from the scope of the present invention.

What is claimed is:—

1. A garment hanger comprising a bow, a pair of spring arms attached to said bow respectively in outwardly spaced relation from the center of the bow, said spring arms having lower inwardly extending portions below the bow, intermediate upwardly extending portions and upper portions extending outwardly respectively toward the ends of said bow above the same, the intermediate portions of said spring arms forming offset noses, the upper portions of said arms normally being urged by the spring tension of said arms into clamping relation with the upper surface of said bow and means carried by said bow with which said noses will engage under spring tension to retain the upper portions of said arms in upwardly spaced relation from said bow as the lower portions of said arms are swung upwardly.

2. A garment hanger comprising a bow, a pair of spring arms applied to the underside of said bow at opposite sides of the center thereof respectively and extending first in

wardly, then upwardly and then outwardly toward the respective ends of the bow, the outwardly extending portions of said arms overlying the upper side of the said bow and 5 being urged by the spring tension of said arms into engagement with the upper surface of said bow, said arms intermediate their lower and upper portions having noses and means carried by said bow with which 10 said noses are adapted to engage by spring tension as the arms are swung upwardly, whereby the nose portions will be caught by said means to retain the upper portions of said arms in spaced relation above the upper 15 surface of said bow.

3. A garment hanger comprising a bow, a pair of spring arms connected to said bow at opposite sides of the center thereof, said spring arms crossing each other below said 20 bow and projecting upwardly to points above said bow and then extending outwardly over said bow to points remote from the points where they are attached to said bow, each of said spring arms intermediate their crossing portions and their outwardly extending portions having offset noses and means with which said noses are adapted to be engaged as said arms are swung upwardly to hold the 25 upper portions of said arms spaced above said bow.

4. A garment hanger comprising a bow, a pair of spring arms applied to said bow in outwardly spaced relation respectively from the center thereof, said spring arms having 30 lower portions extending inwardly and crossing each other, intermediate portions joining said lower portions and extending upwardly above the upper side of said bow and upper portions extending outwardly from said intermediate portions and normally held by the tension of said spring arms in contact with the upper surface of said bow, said intermediate portions having offset noses therein and keeper means carried by said bow and 35 with which the noses of said spring arms are adapted to engage as said arms are swung upwardly to thereby retain said upper portions in spaced relation raised above the upper surface of said bow.

5. A garment hanger comprising a bow, a pair of spring arms applied to said bow outwardly from the central portion thereof at opposite sides thereof respectively, said spring arms being turned on themselves to 40 form coiled springs and projecting below said bow to form lower portions crossing each other, said spring arms from said lower portions extending upwardly to form intermediate portions which project above said bow and said spring arms having upper portions extending respectively outwardly toward the ends of said bow and over the upper surface of said bow from said intermediate portions, said spring arms being 45 under spring tension to normally retain the

upper portions of said arms against the upper surface of said bow and the intermediate portions of said arms having jogs therein forming noses, said noses normally extending below said bow and members applied 50 to said bow with which said noses are adapted to engage as said spring arms are swung upwardly to retain the arms in upwardly swung position with the upper portions of said arms spaced above the upper surface of 55 said bow, said noses being detachable from said means by swinging the intermediate portions of said arms outwardly toward the ends of the bow.

In testimony whereof I affix my signature. 60
